STOCKING

William de Mond, Los Angeles, Calif., assignor to
Sanson Hosiery Mills, Inc., Philadelphia, Pa., a
corporation of Delaware

Application June 10, 1950, Serial No. 10,453

Term of patent 14 years

(Cl. D47—7)

To all whom it may concern:

Be it known that I, William de Mond, a citizen of the United States, and a resident of Los Angeles, county of Los Angeles, State of California, have invented a new, original, and ornamental Design for a Stocking, of which the following is a specification, reference being had to the accompanying drawings, forming a part thereof, wherein:

Figure 1 is a side elevational view of a stocking, showing my new design; and

Figure 2 is an enlarged fragmentary view of the portion of the stocking embraced within the broken line circle of Figure 1.

The present design is characterized by the incorporation in the stocking of a line of stitches formed of a yarn separate and distinct from the yarn or yarns of which the stocking is originally knitted, which said line of stitches extends sub-

stantially parallel to the top edge of the stocking heel and thence downwardly in substantially parallel relation to opposite side edges of said heel, said stitch yarn being of a weight or denier and of a color sufficient to render it of pronounced appearance in the stocking.

I claim:

The ornamental design for a stocking, substantially as shown and described.

WILLIAM DE MOND.
